DIFFERENTIAL FLUID PRESSURE MOTOR

Robert Derrick Tomlin, Harlington, England, assignor to Magnatex Limited, Harlington, England, a British company

Application December 14, 1951, Serial No. 261,618

8 Claims. (Cl. 121—97)

1

The present invention relates to differential fluid pressure motors, and more particularly to suction-operated motors, as used for driving windscreen wipers.

It is the general practice with such motors to arrange for the piston or paddle to move, when the motor is stopped, to a limiting position at one end of its range of movement, so that the wiper blade will be parked at or beyond the limit of its arc of wiping. Often the piston or paddle is moved a short distance beyond one end of its normal stroke or arc of movement, so that the wiper blade will be parked outside its normal arc of wiping. This is effected by constructing the manual control valve for the motor so that when it is moved to its "off" position the source of suction is disconnected from the automatic valve mechanism and is directly connected to one side of the piston or paddle. When in its limiting or parked position, a closure valve carried by the paddle or piston fits against a cup seating surrounding the aperture through which suction is applied, thereby preventing the suction from continuously acting on the piston or paddle packings during parking.

In some wiper installations it is necessary for the wiper to park on the right-hand side and in others on the left-hand side, and this necessitates special motor constructions for each application.

The present invention has for an object to provide a fluid pressure motor of which the piston or paddle can be parked at either one side or the other.

The specification of my copending application Serial No. 209,822 filed February 7, 1951, describes an arrangement for achieving this result by leading the passages connecting with the outlet ports of the automatic valve to ports in the valve seating associated with the manual control valve which is so constructed that in its "on" position it connects these ports to opposite sides of the motor whilst when in one or the other of two "off" positions it connects either one side or the other of the motor directly to the source of suction whereby the paddle will be parked on that side.

The motor described in that specification employs a manual control valve arrangement which may involve special fitting when the motor is to be fitted as a replacement for an existing motor which is constructed for right-hand or left-hand parking only. This particularly applies in the case of the smaller types of suction motor in which the manual control valve is arranged for

2

sliding movement in a direction parallel to the motor spindle and to either one side or the other of the centre of the motor cover depending upon the side to which the paddle is to be parked.

5 A further object of the present invention is to provide a differential fluid pressure motor of which the piston or paddle can be parked at either one side or the other, and which is so constructed that it can be used as a replacement for existing motors constructed for parking at only one side or the other.

Moreover, in order to comply with the design requirements of different car manufacturers, the windscreen wiper motors have to be built with 15 different lengths of driving shaft, different lengths of bushings through which this shaft passes, and different head fittings on the shaft. Thus a stockist of replacement motors has to carry a stock of several motors with different 20 lengths of shaft and bushing, and different head fittings in order to meet all the requirements which may be placed upon him.

A still further object of the invention, therefore, is to provide a motor of which the driving 25 shaft and bushing are readily interchangeable, whereby a stockist may fit the requisite shaft and bushing to a standardised motor unit to produce the desired motor.

According to the invention, the motor is provided with two manual control valve seatings, 30 the valve seatings having ports therein which are so connected to the motor chamber, the source of suction and the automatic valve that each valve seating, when associated with a control valve, is adapted to effect starting and stopping of the motor and to park the paddle at the corresponding side of the motor, a control valve being associated with either one or other of the valve seatings depending upon the side to which 35 the paddle is to be parked, whilst the second valve seating is associated with a member for connecting together the ports thereof leading respectively to the corresponding side of the motor and the corresponding outlet port of the automatic valve. The member associated with 40 the second valve seating may also comprise a control valve which is left in its "on" position. To change the parking position it is then only necessary to connect one or other of the control valves for manual operation, the other control valve being left in its "on" position. Means may be provided for locking or holding the appropriate control valve in its "on" position.

Alternatively, the member associated with the 55 second valve seating may comprise a special

member which is simply secured in position, this member and the control valve being interchangeable to select the side of the motor at which the piston or paddle is to be parked.

The invention also consists in a suction motor of the oscillating paddle type wherein the motor cover is provided with two control valve seatings disposed at opposite sides of the centre of the cover, each valve seating having ports leading respectively to a connection for a source of suction and to the inlet port of the automatic valve, the outlet ports of the automatic valve being connected respectively to ports in the respective valve seatings which are also provided with further ports connecting respectively with the corresponding sides of the motor, and wherein a control valve is provided which is fitted to one valve seating and is formed with ports or passages which, when the valve is in its "on" position, it connects the source of suction to the central inlet port of the automatic valve and the associated outlet port of the automatic valve to the corresponding side of the motor, and in its "off" position, disconnects the source of suction from the inlet port of the automatic valve and directly connects the source of suction to the corresponding side of the motor, and wherein a further member is provided which is fitted to the other of the valve seating and connects the associated outlet port of the automatic valve to the corresponding side of the motor.

According to a further feature of the invention, the motor is constructed with a socket portion for receiving the end of the bushing, said socket portion surrounding the end of the motor shaft and being constructed of two or more parts which can be separated without otherwise disassembling the motor, the bushing being provided with an enlargement at its end which is adapted to fit into a corresponding recess in the socket portion so that the bushing will be retained therein against longitudinal movement when the socket parts are assembled around the bushing end, there being fitted within the bushing an extension shaft, the end of which is adapted to interengage or couple with the end of the motor shaft when the bushing, with the extension shaft therein, is secured in position.

In carrying out the invention, the motor can be constructed as a conventional paddle type motor except that two manual control valve seatings are provided which are disposed on opposite sides of the centre of the cover, the two outlet ports from the automatic valve leading to their corresponding sides of the motor through ports in that one of the valve seatings located on the corresponding side of the cover. Thus, both said outlet ports lead to their corresponding sides of the motor through ports in one or other of the control valve seatings.

In one embodiment, only a single manual control valve is provided which may be fitted selectively to either one or other of the valve seatings depending upon the side to which it is desired that the paddle should park, the other valve seating being fitted with a fixed member provided with a passage for connecting the associated outlet port from the automatic valve to the corresponding side of the motor, said member also seating over and preventing air leakage to the port leading to the inlet port of the automatic valve. The control valve and fixed member are interchangeable to select the side of the motor at which the paddle is to be parked.

In another embodiment, each valve seating is

fitted with a conventional control valve movable between "on" and "off" positions. By leaving one control valve permanently in the "on" position, the motor can be started and stopped by moving the other control valve, the paddle parking on the same side of the motor as the actuated control valve when it is moved to its "off" position.

The control valve which is permanently in the "on" position permanently connects that side of the motor to the corresponding outlet port of the automatic valve, whilst the movable control valve either, in its "on" position, connects the suction supply to the inlet port of the automatic valve and the adjacent end of the motor to the corresponding outlet port of the automatic valve or, in its "off" position, directly connects the source of suction to the adjacent end of the motor and simultaneously uncovers the port in the valve seating leading to the inlet port of the automatic valve so that this inlet port is connected to the atmosphere. The opposite end of the motor will therefore be vented to atmosphere irrespective of the position of the automatic control valve.

Only that control valve which is to be moved need be fitted with a handle or like member for manual operation; preferably the other control valve is associated with means for holding it in its "on" position. For example each control valve may be provided with a spigot adapted to be engaged with a slidable manual control member. This control member may be provided with an extension piece such as a rod carrying the operating knob, this extension piece being interchangeable from one control member to the other depending upon which valve is to be operated. The control member not fitted with the extension piece may be locked in position by a screw or in any other convenient manner. Alternatively, only one of the control members may be provided with slots so that it is slidable relative to the screws holding the valve assembly in position, the other control valve having its spigot engaging with a fixed member which may be similar to a control member but without the slots for permitting sliding movement, this fixed member having apertures through which the assembly screws pass and thereby hold the associated control valve on its "on" position. The fixed member and slidable control member are interchangeable to select the side to which the paddle is to be parked.

Each control valve seating may be associated with a separate suction supply connection, that which is not in use being sealed off; for example the motor may be provided with a threaded tubular connector or nipple and a threaded plug which may be interchangeably fitted in threaded apertures in the casting leading respectively to the suction supply ports in the respective valve seatings.

The passages leading from the valve seatings to opposite sides of the motor preferably terminate in two cup seatings arranged on the underside of the cover and adapted to co-operate respectively with closure or sealing members carried from opposite sides of the paddle so that when the motor is in a parked position, the source of suction acts on a closure member and does not act continuously on the paddle packings.

In order to provide for the interchangeable extension shaft and bushing, the top cover of the motor housing is made with the half socket portion thereof which surrounds the shaft bushing

separate from the remainder of the cover and secured thereto, or to the bottom half of the motor housing, by means of screws or the like. The motor shaft projecting from the paddle is made of reduced length, its end terminating short of the recess adapted to receive the enlarged collar at the end of the shaft bushing, and being formed with flats or with a transverse slot or ridge adapted to engage with a corresponding socket or with a ridge or slot in the end of an extension shaft carried in the bushing. This extension shaft is preferably captive in the bushing, so that when a bushing is fitted to the motor housing with its collar in the recess, the end of the extension shaft will be automatically coupled with the end of the motor shaft. By securing the half-socket portion of the cover in position the bushing will be retained with the motor shaft and extension shaft coupled together. The collar on the bushing is preferably of polygonal form so that when the cover half-socket portion is screwed down it will lock the bushing against rotary as well as longitudinal movement.

With the construction described, it will be appreciated that bushings of different lengths and extension shaft of different length and with different end fittings may be interchangeably mounted in and secured to the motor housing without it being necessary for the motor cover to be removed.

In order that the invention may be clearly understood, embodiments thereof will now be described by way of example with reference to the accompanying drawings in which:

Fig. 1 is a perspective view of a suction operated windscreens wiper motor embodying the invention,

Fig. 2 is a front elevation of the motor with the automatic valve cover plate removed,

Fig. 2a is a perspective view of the movable element of the automatic valve showing the reverse face to that visible in Fig. 2,

Fig. 3 is a plan view of the motor with the elements of the control valve and fixed member removed so as to show the control valve seatings,

Fig. 4 is an exploded perspective view of the operative control valve shown on the right hand side of the motor shown in Fig. 2,

Fig. 4a is a perspective view of the control valve element showing the under face thereof,

Fig. 5 is a perspective view of the control valve seating and fixed member shown on the left hand side of the motor in Fig. 1,

Fig. 5a is a perspective view of the fixed member shown in Fig. 5 but showing the reverse face thereof,

Fig. 6 is a perspective view of a control valve with the cover removed and having a screw for locking the control valve in the "on" position,

Fig. 7 is a perspective view of a modified valve construction which is held permanently in the "on" position,

Fig. 8 is an exploded perspective view of the bushing and detachable extension shaft to which the wiper blade is attached,

Fig. 8a is a perspective view of one of the elements shown in Fig. 8 and showing the opposite face thereof, and

Fig. 9 is a sectional view of the detachable extension shaft and bushing shown in Fig. 8.

The motor illustrated in the drawings is a suction operated windscreens wiper motor which is basically of known design and comprises a casing 1 fitted with a cover 2 forming a sealed piston chamber in which a piston 3 of the paddle type

oscillates a rocker shaft 4 having an extension 4a which drives a wiper blade, the paddle dividing the chamber in an air-tight manner into two compartments.

5 The cover 2 is provided with aligned passages 5 and 6 (Fig. 3) leading to control valve seatings 7 and 8 at opposite ends of the motor by means of which the passages 5 and 6 can be put into communication with suction supply conduits 9 and 10 respectively as will hereinafter appear. Either of these suction supply conduits can be connected to a source of suction such as the intake manifold of an internal combustion engine. In Figs. 1 and 3 conduit 10 is fitted with a detachable screw threaded nipple 11 for connection to the suction source and conduit 9 is sealed by means of a screw threaded plug 12. Nipple 11 and plug 12 are interchangeable according to which side of the motor it is desired that the wiper blade should park.

20 The passages 5 and 6 lead to automatic valve mechanism indicated generally at 13 for connecting the source of suction to opposite sides of the paddle in order to reciprocate the paddle, the 25 valve mechanism also controlling the admission of atmospheric air to the side of the paddle not for the time being under suction. The valve mechanism 13 is made automatic in action under control of the swinging movement of the paddle 30 so that the valve mechanism is automatically reversed each time the paddle reaches the limit of its normal swing in each direction. In the embodiment shown, this automatic valve mechanism is of known construction comprising a semi-35 rotary disc valve 14 (Figs. 1, 2, 2a and 3) of segmental form having an arcuate channel 15 therein and movable in an arc between two positions by means of a snap action mechanism embodying a rocker 16 actuated by a flat on the rocker shaft 4. The valve operates against a surface 17 (Fig. 2) of the cover 2 having three valve ports 18, 19 and 20 disposed in an arc therein so as to co-operate with the channel 15 in the valve 14. The details of this automatic valve mechanism are 40 known and form no part of this invention, and will not therefore be described in detail. It need only be mentioned that the valve 14 always covers the middle port 19 and is operated so as also to cover the ports 18 and 20 alternately and thereby 45 effect communication of the ports 18 and 20 alternately with the port 19 by way of the channel 15 in the valve. The ports 18 and 20 are each open to the atmosphere when not covered by the valve. The port 19 leads into the passages 5 and 6, while the port 18 leads into a passage 21 which 50 communicates through ports in the left hand control valve seating with a passage 22 which leads to the piston chamber on one side of the paddle within a cup seating 23. The port 20 55 leads into a passage 24 which communicates through ports in the right hand control valve seating with a passage 25 leading to the piston chamber on the other side of the paddle within a cup seating 26. The paddle is provided with 60 sealing closures 27 and 28 arranged to co-operate with the cup seatings 23 and 26 respectively when suction is continuously applied to one of those seatings so that the suction is operative to hold the closure in sealing contact with the cup seating 65 and with the wiper blade parked on the corresponding side of the motor according to the selected arrangement of the control valves.

70 The passages 6, 10, 24 and 25 terminate in ports 6a, 10a, 24a and 25a in the valve seating 8 which 75 is cast integrally with the cover 2 and with which

co-operates a slide valve 29 which controls the operation of the motor. The slide valve is provided with channels 30 and 31 (Fig. 4a) which, when the slide valve is in its forward or "on" position as shown in Fig. 1 connect together the ports 6a and 18a and ports 24a and 25a respectively. In this position the source of suction is connected through the port 18a, channel 30, and port 6a to the port 19 of the automatic valve mechanism 13 for the automatic operation of the motor, the port 19 being connected alternately to ports 18 and 29 as above mentioned. Port 29 is connected, in this position of the valve, through passage 24, port 24a, channel 31, port 25a and passage 25, to the piston chamber on the right hand side of the motor. In the rearward or "off" position of the valve, port 18a is connected directly to port 25a through the channel 30 so that suction is applied directly to the piston chamber to hold the closure 28 on the paddle in continuous sealing contact with the cup seating 26 so that the wiper arm is parked on the right hand side of the motor as viewed in the drawings. In this position of the valve channel 31 becomes inoperative as it merely overlies the L-shaped port 25a and port 6a is vented to atmosphere through slot 44.

Valve seating 7 is similar to valve seating 8 but is of opposite hand and has ports 5a, 8a, 21a and 22a communicating respectively with the passages 5, 9, 21 and 22. Port 21a is permanently connected to port 22a through a channel 32 in the underface of a fixed sealing member 33 of rubber or other suitable material having holes 34 and 35 which fit over posts 36 and 37 respectively. These posts have threaded bores for receiving retaining screws 146, 141 for a cover member 142 (Fig. 1) as can be seen more clearly from Fig. 4 which shows the detailed construction of the right hand control valve. In Fig. 4, 38 and 39 are posts similar to posts 36 and 37 of Fig. 5 and receive screws 40 and 41 for retaining in position the cover member 42. Member 33 maintains port 18 in continuous communication with the passage 22 leading into the piston chamber on the left hand side of the drawing.

The right hand control valve 29 is formed with slots 43 and 44 through which the posts 38 and 39 pass and this valve is held in sealing contact with a gasket 45 by means of a compression spring 46 guided by a spigot 47 which engages in an aperture 48 in a slideable operating member 49 having slots 50 and 51 for accommodating the posts 38 and 39. The slideable operating member 49 is fitted with a stud 52 having a transverse bore for receiving a rod 53 which carries at its end a knob 54 by which the member 49 can be manually operated. Rod 53 is held in position by set screw 55.

If it is desired to adapt the motor for parking on the left hand side, control valve 29 and its associated elements are substituted for the fixed member 33 on the left hand side of the motor and member 33 is mounted on valve seating 8 so as to connect together ports 24a and 25a. The positions of nipple 11 and plug 12 are also reversed.

In a modified arrangement illustrated fragmentally in Fig. 6 of the drawings, two identical control valves are provided on both sides of the motor and the valve seatings 7 and 8 are formed with threaded apertures for receiving a screw 55 which is screwed into one of the valve seatings to hold locked in the "on" position the corresponding operating member 49 and valve 29. The operating rod 53 carrying the knob 54 is secured

to the operative control valve by means of the set screw 56.

A still further modified arrangement is illustrated in Fig. 7 in which one of the control valves 5 is provided with a member 49a in place of the operating member 49, this member 49a having apertures therein arranged to fit the posts 36 and 37 or 38 and 39 so that member 49a holds the control valve 29 permanently in the "on" position with the port 21a permanently connected to the port 22a, or the port 24a permanently connected to the port 25a, as the case may be. Members 49 and 49a are interchangeable according to the side on which it is desired that the wiper blade should park.

In order to provide a motor in which the driving shaft for the wiper blade and the shaft bushing are readily interchangeable so that a stockist may fit the requisite shaft and bushing to a standardised motor unit to produce the desired motor, the motor is constructed with a socket portion for receiving the end of the bushing as illustrated in Figs. 8, 8a and 9. This socket portion surrounds the end of the motor shaft 4 and is constructed of two parts. One part consists of a half hexagonal recess 57 in the motor casing 1 and the other part is formed by a stirrup member 58 having a complementary half hexagonal recess 59 and secured in co-operating relationship with recess 57 by screws 60 and 61. The shaft bushing 62 is formed at one end with a hexagonal flange 63 which fits into the hexagonal sockets 57, 59 and is locked in position therein by a semi-circular flange 64 at the front face of recess 59, which flange fits over the bushing 62. The end of the motor shaft 4 is formed with flats 65 for co-operating in driving relation with a socket member 66 carried on the extension shaft 4a which is mounted within the bushing 62. Extension shaft 4a is formed at its outer end to receive the wiper blade or an operating arm for the blade or coupled blades. In the embodiment shown it is formed with a boss 67 having flats 68 thereon for co-operating with a correspondingly shaped socket in the wiper blade or operating arm. The boss terminates in a threaded portion 69 for receiving a retaining nut. The bushing 62 is threaded externally at its outer end at 70 to receive a retaining nut 71.

It will be seen that by reason of the socket member 66 on one end of the extension shaft 4a and the boss 67 on the other end, the extension shaft is captive within the bushing 62 so that when the bushing is fitted to the motor housing with its flange in the socket, the end of the extension shaft will be automatically coupled to the end of the motor shaft. By securing the half socket portion 58 in position the bushing will be retained in position with the motor shaft 4 and the extension shaft 4a coupled together.

The socket 57, 59 may be of any desired polygonal form or may be circular and may be screwed to the cover 2 instead of to the casing 1. The end of the shaft 4 may be shaped in any convenient manner to co-operate in driving relation with the correspondingly shaped end of extension shaft 4a.

While particular embodiments of the invention have been described with reference to the accompanying drawings, these are by way of illustration only and not by way of limitation and the construction may be modified without departing from the scope of the invention as defined in the appended claims.

I claim:

1. A differential fluid pressure motor comprising a housing, a paddle mounted for oscillatory movement within the housing, a first valve seating on the housing having an inlet port and first and second outlet ports, an automatic valve member movable over said first valve seating by the movement of said paddle and having a passage therein arranged to connect said inlet port alternately to said outlet ports, a second valve seating on said housing having a port connecting with said inlet port, a port connecting with said first outlet port, a port connectable to a source of supply of fluid at other than atmospheric pressure and a port leading into the housing at one side of the paddle, a third valve seating on said housing having a port connecting with said inlet port, a port connecting with said second outlet port, a port connectable to a source of supply of fluid at other than atmospheric pressure and a port leading into the housing at the other side of the paddle, a manually operable valve member movable over one of said second and third valve seatings between an "on" position and an "off" position and having a first passage therein arranged to connect the associated port connectable to the source of fluid supply to, in the "on" position, the associated port connected to said inlet port and, in the "off" position, to the associated port leading into the housing, and said manually operable valve member having a second passage therein arranged to connect the associated port leading into the housing to, in the "on" position, the associated port connected to an outlet port and to disconnect said ports in the "off" position, and a fluid conducting member mounted on the other of said second and third valve seatings and connecting the port therein which is connected to one of said outlet ports to the port therein leading into the housing.

2. A differential fluid pressure motor comprising a housing, a paddle mounted for oscillatory movement within the housing, a first valve seating on the housing having an inlet port and first and second outlet ports, an automatic valve member movable over said first valve seating by the movement of said paddle and having a passage therein arranged to connect said inlet port alternately to said outlet ports, a second valve seating on said housing having a port connecting with said inlet port, a port connecting with said first outlet port, a port connectable to a source of supply of fluid at other than atmospheric pressure and a port leading into the housing at one side of the paddle, a third valve seating on said housing having a port connecting with said inlet port, a port connecting with said second outlet port, a port connectable to a source of supply of fluid at other than atmospheric pressure and a port leading into the housing at the other side of the paddle, a manually operable valve member movable over one of said second and third valve seatings between an "on" position and an "off" position and having a first passage therein arranged to connect the associated port connectable to the source of fluid supply to, in the "on" position, the associated port connected to said inlet port and, in the "off" position, to the associated port leading into the housing, and said manually operable valve member having a second passage therein arranged to connect the associated port leading into the housing to, in the "on" position, the associated port connected to an outlet port and to disconnect said ports in the "off" position, and a fluid conducting member fixed on the other

of said second and third valve seatings and connecting the port therein which is connected to one of said outlet ports to the port therein leading into the housing, said fluid conducting member also seating over and preventing fluid leakage through the associated port leading to said inlet port, and said manually operable valve member and said fluid conducting member being interchangeable to select the side of the motor at which the paddle is to be parked.

3. A differential fluid pressure motor comprising a housing, a paddle mounted for oscillatory movement within the housing, a first valve seating on the housing having an inlet port and first and second outlet ports, an automatic valve member movable over said first valve seating by the movement of said paddle and having a passage therein arranged to connect said inlet port alternately to said outlet ports, a second valve seating on said housing having a port connecting with said inlet port, a port connecting with said first outlet port, a port connectable to a source of supply of fluid at other than atmospheric pressure and a port leading into the housing at one side of the paddle, a third valve seating on said housing having a port connecting with said inlet port, a port connecting with said second outlet port, a port connectable to a source of supply of fluid at other than atmospheric pressure and a port leading into the housing at the other side of the paddle, a manually operable valve member movable over one of said second and third valve seatings between an "on" position and an "off" position and having a first passage therein arranged to connect the associated port connectable to the source of fluid supply to, in the "on" position, the associated port connected to said inlet port and, in the "off" position, to the associated port leading into the housing, and said manually operable valve member having a second passage therein arranged to connect the associated port leading into the housing to, in the "on" position, the associated port connected to an outlet port and to disconnect said ports in the "off" position, and a fluid conducting member of resilient material fixed over the other of said second and third valve seatings and connecting the port therein which is connected to one of said outlet ports to the port therein leading into the housing, said fluid conducting member also seating over and preventing fluid leakage through the port leading to said inlet port.

4. A differential fluid pressure motor comprising a housing, a paddle mounted for oscillatory movement within the housing, a first valve seating on the housing having an inlet port and first and second outlet ports, an automatic valve member movable over said first valve seating by the movement of said paddle and having a passage therein arranged to connect said inlet port alternately to said outlet ports, a second valve seating on said housing having a port connecting with said inlet port, a port connecting with said first outlet port, a port connectable to a source of supply of fluid at other than atmospheric pressure and a port leading into the housing at one side of the paddle, a third valve seating on said housing having a port connecting with said inlet port, a port connecting with said second outlet port, a port connectable to a source of supply of fluid at other than atmospheric pressure and a port leading into the housing at the other side of the paddle, and two manually operable valve members respectively associated

with and movable over each of said second and third valve seatings between an "on" position and an "off" position, each manually operable valve member having a first passage therein arranged to connect the associated port connectable to the source of fluid supply to, in the "on" position, the associated port connected to said inlet port and, in the "off" position, to the associated port leading into the housing, and also having a second passage therein arranged to connect the associated port leading into the housing to, in the "on" position the associated port connected to an outlet port and to disconnect said ports in the "off" position.

5. Motor as claimed in claim 4, comprising also operating means selectively connectable to either one of said manually operable valve members, and means securing the other of said manually operable valve members in its "on" position.

6. Motor as claimed in claim 5, wherein each of said second and third valve seatings has a threaded aperture, and a screw screwable into either of said threaded apertures according to which of the manually operable valve members is to be held in the "on" position, said apertures being so located that said screw holds the associated manually operable valve member in the "on" position.

7. A differential fluid pressure motor comprising a housing, a paddle mounted for oscillatory movement within the housing, a first valve seating on the housing having an inlet port and first and second outlet ports, an automatic valve member movable over said first valve seating by the movement of said paddle and having a passage therein arranged to connect said inlet port alternately to said outlet ports, a second valve seating on said housing having a port connecting with said inlet port, a port connecting with said first outlet port, a port connectable to a source of supply of fluid at other than atmospheric pressure and a port leading into the housing at one side of the paddle, a third valve seating on said housing having a port connecting with said inlet port, a port connecting with said second outlet port, a port connectable to a source of supply of fluid at other than atmospheric pressure and a port leading into the housing at the other side of the paddle, two manually operable valve members respectively associated with and movable over each of said second and third valve seatings between an "on" position and an "off" position, each manually operable valve member having a first passage therein arranged to connect the associated port connectable to the source of fluid supply to, in the "on" position, the associated port connected to said inlet port and, in the "off" position, to the associated port leading into the housing and also having a second passage therein arranged to connect the associated port leading into the housing to, in the "on" position the associated port connected to an outlet port and to disconnect said ports in the "off" position, a cover for each of said manually operable valve members, means for holding each

cover to its associated valve seating, a slidable operating member operatively connected to one of said manually operable valve members, and a non-sliding member apertured to permit the passage therethrough of the associated cover holding means in non-sliding relation and operatively connected to the other manually operable valve member to hold it permanently in the "on" position, said slidable operating member and said non-sliding member being interchangeable to select the side of the motor at which the paddle is to be parked.

8. A differential fluid pressure motor comprising a housing, a paddle mounted for oscillatory movement within the housing, a first valve seating on the housing having an inlet port and first and second outlet ports, an automatic valve member movable over said first valve seating by the movement of said paddle and having a passage therein arranged to connect said inlet port alternately to said outlet ports, a second valve seating on said housing having a port connecting with said inlet port, a port connecting said first outlet port, a port leading to a first inlet conduit in the housing and a port leading into the housing at one side of the paddle, a third valve seating on said housing having a port connecting with said inlet port, a port connecting with said second outlet port, a port leading to a second inlet conduit in the housing and a port leading into the housing at the other side of the paddle, a sealing plug in one of said inlet conduits and a connecting member in the other conduit for connecting the motor to a source of supply of fluid at other than atmospheric pressure, a manually operable valve member movable over the valve seating associated with the connecting member between an "on" position and an "off" position and having a first passage therein arranged to connect the associated port leading to the connecting member to, in the "on" position, the associated port connected to said inlet port and, in the "off" position, to the associated port leading into the housing, and said manually operable valve member having a second passage therein arranged to connect the associated port leading into the housing to, in the "on" position the associated port connected to an outlet port and to disconnect said ports in the "off" position, and a fluid conducting member mounted on the valve seating associated with the sealing plug and connecting the port therein which is connected to one of said outlet ports to the port therein leading into the housing, said manually operable valve member and said connecting member being interchangeable respectively with said fluid conducting member and said sealing plug.

ROBERT DERRICK TOMLIN.
